DESIGN FOR AN ELECTRIC SHAVER

Wendell L. Martin, Shaker Heights, Ohio

Application November 14, 1939, Serial No. 88,279

Term of patent 7 years

To all whom it may concern:

Be it known that I, Wendell L. Martin, a citizen of the United States, residing at Shaker Heights, in the county of Cuyahoga and State of Ohio, have invented a new, original, and ornamental Design for Electric Shaver, of which the following is a specification, reference being had to the accompanying drawing, forming part thereof.

Figure 1 is a view looking into the operating end of the shaver, namely, a view looking in the direction indicated by the arrow 1 in Figure 2, while the rear end of Figure 1 is plain.

looking in the direction indicated by arrows 2 in Figures 1, 3 and 4.

Figure 3 is an edge view of same, namely, a view looking in the direction indicated by arrows 3 in Figures 1 and 2.

Figure 4 is another edge view of same, namely, a view looking in the direction indicated by arrows 4 in Figures 1 and 2.

I claim:

The ornamental design for an electric shaver, as shown and described.

WENDELL L. MARTIN.
